UNITED STATES PATENT OFFICE

2,497,616

OIL PUMP DRIVE FOR STEAM TURBINES

Karl MacDonald, Wellsville, N. Y., assignor to
Worthington Pump and Machinery Corporation,
Harrison, N. J., a corporation of Delaware

Application September 15, 1945, Serial No. 616,549

5 Claims. (Cl. 184—6)

1

This invention relates to steam turbines, and more particularly to a novel type of drive for driving an oil pump to provide forced feed lubrication for steam turbines.

An object of the present invention is to provide a drive mechanism for driving a forced feed lubrication pump which may be employed in connection with steam turbines of some sizes, such as single stage turbines, without requiring extensive changes in the turbine parts, changes in its shaft, or causing an increase in the overall length of the turbine.

More specifically, the present invention comprehends the use of the governor disc of the governor of a steam turbine as the driving element from which power is taken to drive the lubricating pump.

With these and other objects in view, as may appear from the accompanying specification, the invention consists of various features of construction and combination of parts, which will be first described in connection with the accompanying drawings, showing an oil pump drive for steam turbine of a preferred form embodying the invention, and the features forming the invention will be specifically pointed out in the claims.

In the drawings:

Figure 1 is a view partly in elevation and partly in longitudinal section of the improved oil pump 30 drive for turbines and taken on the line 1—1 of Figure 2.

Figure 2 is a vertical cross section through the oil pump drive mechanism and taken on the line 2—2 of Figure 1.

Referring more particularly to the drawings, 1 indicates a steam turbine of any approved construction which includes a governor mechanism generically indicated at 2 which controls the speed of operation of the turbine in the usual manner. The governor mechanism includes the usual type of disc 3 which is rotated by the main drive shaft 4 of the turbine and which carries the usual governor weights 5. The governor disc 3 has spiral gear teeth 5 either cut upon its perimeter or mounted thereon in any suitable manner. The spiral gear teeth 5 mesh with the spiral teeth 6 of a pinion 7 which is mounted upon the drive shaft 8 of the oil pump structure 9. The oil pump structure 9 as shown in 35 the drawings is of the usual inner meshing gear

2

type impellers, e. g., the impeller 10 is mounted on the main drive shaft 8 and meshes with the impeller 11 for pumping the lubricating oil from the oil reservoir 12 through the pump 9 and the usual required piping mechanism 14 to the various bearings (not shown) of the turbine. A suitable drain pipe 15 is provided for returning the oil to the oil reservoir 12.

If conditions require, or if it is so desired, an 10 intermediate or idler gear may be interposed between the gear teeth on the perimeter of the governor disc 3 and the pinion 6.

15 It will be understood that the invention is not to be limited to the specific construction or arrangement of parts shown, but that they may be widely modified within the invention defined by the claims.

What is claimed is:

1. The combination with a steam turbine assembly including a governor embodying a governor disc, of a lubricating oil pump, said governor disc having a spiral gear cut upon its perimeter, and a spiral gear meshing with said governor disc carried spiral gear and connected to said oil pump for driving the oil pump by rotation of the governor disc.

2. The combination with a steam turbine assembly including a governor embodying a governor disc, of a lubricating oil pump, said governor disc having a spiral gear cut upon its perimeter, a driven shaft for said oil pump, a spiral gear on said drive shaft and meshing with the spiral gear on the perimeter of the governor disc for driving the oil pump by rotation of the governor disc.

KARL MACDONALD.
